UNITED STATES PATENT OFFICE.

JOSEPH SILBERMAN AND LOUIS KAHN, OF BALTIMORE, MARYLAND.

NECKTIE.

1,402,903.

Specification of Letters Patent. Patented Jan. 10, 1922.

Application filed August 23, 1919. Serial No. 319,377.

To all whom it may concern:

Be it known that we, JOSEPH SILBERMAN and LOUIS KAHN, citizens of the United States, residing at Baltimore, in the State 5 of Maryland, have invented a certain new and useful Improvement in Neckties, of which the following is a full, clear, and exact description.

The object of this invention is to provide a necktie, especially of the four-in-hand variety, with a so-called "slip-easy" or frictionless lining whereby the necktie may be readily adjusted without undue straining with collars of the fold-over or turn-down 15 type.

Although we have referred to the invention as applied to four-in-hand ties, it will be obvious that it may be applied to other types of ties with similar beneficial results.

20 The invention consists of a necktie having a lining strip applied to the inner side in any usual or approved manner, so as to present a flat smooth surface, and having one or both of its ends secured to the tie 25 and its interlining by a series of massed overedge stitches, such as employed in making buttonholes, buds, and the like, as we will proceed now to explain and finally claim.

30 In the accompanying drawings illustrating the invention, in the several figures of which like parts are similarly designated, Figure 1 is a plan view of a necktie having its ends reversed to show the back. Fig. 2 is a plan view of one end of the tie with the 35 face material broken out to expose the interlining. Fig. 3 is a plan view illustrating the application of the end finish of the lining to the smaller end of the necktie.

As already indicated, the invention may be 40 applied to any type of tie, but the drawings show a four-in-hand tie having wide ends 1 and 2, one end being larger and wider than the other, as usual. 3 is the lining strip of any material having such a surface as will 45 permit the tie to be slipped easily in the collar to effect the necessary adjustment to make the knot, or in other words, to tie the tie. This lining extends nearly to the ends of the tie, and may be applied to it in any 50 approved way, preferably so as to conceal the stitches along its longitudinal edges and by which it is connected to or incorporated in the body of the tie. The end 4 of this lin-

ing is secured to the folds of the tie and also to the interlining 5 by means of massed over-edge stitches 6, this end of the lining preferably being V-shaped so as to present the least possible obstruction. The stitches 6 may be such as used in working buttonholes or buds.

The end 7 may be secured between the folds of the opposite end of the tie in any usual or approved manner, or as shown in Fig. 3 at 8, this end also may be V-shaped and stitched down as heretofore described 65 with reference to the end 4.

When the ends are finished as heretofore explained, it is not necessary to hem or even baste the end of the lining, and hence an economy in manufacture is effected.

The massed overedge stitches which serve to fasten the ends of the lining provide a very firm anchorage for this lining, and tend to keep the lining smooth and unwrinkled so that its "slip-easy" function 75 remains unimpaired during the life of the tie; and not only is this utilitarian function obtained, but in addition the construction provides a very slight finish.

Variations in the details of construction 80 and the form of the ends of the lining are permissible within the scope of the invention and the claims following:

What we claim is:—

1. A necktie, having an interlining and a 85 slip-easy lining strip provided with a V-shaped end and massed overedge stitches connecting the end only of the lining to the material of the necktie and also to its interlining.

2. A necktie, having an interlining and a slip-easy lining strip provided with V-shaped 90 ends, said ends being finished and applied to the material of the tie and to its interlining by means of massed overedge stitches 95 disposed along the edges of the V-shaped ends only and connecting the lining, the material and the interlining.

In testimony whereof we have hereunto set our hands this 22nd day of August, A. D. 100 1919.

JOSEPH SILBERMAN.
LOUIS KAHN.
